UNITED STATES PATENT OFFICE.

MALCOLM D. RIKER, OF DOVER, NEW JERSEY, ASSIGNOR TO MCKIERNAN-TERRY DRILL COMPANY, OF NEW YORK, N. Y., A CORPORATION OF NEW JERSEY.

PILE-PULLING APPARATUS.

Application filed July 10, 1920. Serial No. 395,335.

To all whom it may concern:

Be it known that I, MALCOLM D. RIKER, a citizen of the United States, and a resident of Dover, in the county of Morris and State 5 of New Jersey, have invented certain new and useful Improvements in Pile-Pulling Apparatus, of which the following is a specification.

My invention relates to devices for pulling piling, particularly sheet piling, by means of power apparatus. The device to which this invention appertains is designed to be used in conjunction with a pneumatic hammer pile pulling rig for the purpose of 10 starting the pile and breaking the joint between the piling to be withdrawn and the adjacent piling, after which the piling may be completely removed by the pile pulling rig without severe strain on the derrick.

It is the object of the invention to provide a well constructed, compact, simple, inexpensive and efficacious pile pulling attachment which may be readily transported and placed in position for use.

Another object of the invention is the provision of a strongly built device which will co-operate with a power hammer to start firmly embedded piling.

With the foregoing and other objects in view which will become apparent as the description proceeds, my invention resides in the combination and arrangement of parts and in the details of construction described in the specification and particularly pointed out in the appended claims, it being understood that I do not limit myself to the precise embodiment of the invention herein disclosed and changes can be made within the scope of what is claimed without departing from the spirit of the invention.

In the accompanying drawings—

Figure 1 is an elevation of the device in position for use in connection with a pile pulling rig.

Figure 2 is a plan view of the attachment showing the arrangement of bolts and spreaders, the attached cables and the piston rod being in section, and

Fig. 3 is an enlarged elevation, partly in section, of the hammer and hydraulic puller.

Similar reference numerals refer to similar parts throughout the several views.

In the drawings,

The numeral 10 designates the main casing of a well known form of pneumatic

hammer, the enlargement 9 containing the usual valves and air ports for the control and operation of the hammer. The casing is supported by a cable 8 passing under the casing and loops over a hook 7 suspended 60 from a derrick arm by a cable 6. A cable sling 5, in this instance, comprising three cables, passes over the filling block 4 between the guides 3, 3', the ends of the sling being fastened to the piling by the clamp 2. 65

The retaining ring 1 passes around the supporting cable and the cable sling, holding them in position and at the same time serving to keep the hammer casing upright, there being no other means used for holding 70 the parts together. This retaining ring 1 rests on the anvil block 11, fits into an undercut groove of the filling block 4 and rides in the undercut portions of the guides 3'. 75

At the lower end of the casing 10 is a hydraulic cylinder 20 in which is a piston 19, fluid passing into the cylinder above the piston by means of the connection 18. The piston rod 17 is attached to the piston 19 80 and is pivotally attached at the lower end 16 to the support lever arm 15 fulcrumed as at 14 to the post 13 which has an inverted U-shaped end 12 pressing down on the embedded piling. The other end 21 of the support lever arm 15 is anchored to the embedded piling by the cables 22, 23. 85

A slack cable 24 is attached from the casing to the anchored end of the lever arm and supports the free end of this part of the 90 mechanism when it is not in use as, for example, when the pile has been started, the anchoring cables 22, 23 detached, and the pile pulling rig is in action completing the pulling operation. 95

The support lever arm 15 as shown comprises two plates 25, 26, having the spacers 27, 27 set between them, allowing the insertion of the post 13 between the plates and permitting the lever to rock freely on the 100 pivot pin 14.

In use the entire apparatus is placed in position as shown in Figure 1. Fluid is admitted above the piston 19 by connection 18 and there is a reaction between the piston 19 105 and the cylinder 20. The piston cannot move downward materially as it is anchored by the cables 22, 23. Consequently the casing moves upward against the cable sling 5 thus exerting a steady and forceful pull on 110

the clamp 2 and starting the pile to which this clamp is attached, the adjacent piling being held down by the pressure of the post 13. The derrick arm takes up the slack of 5 the cable 8.

10 The hammer may be used to augment the effect of the hydraulic device to start and break the joints, after which the hydraulic device may be released and the hammer used 15 to complete the withdrawal of the pile, the action of the hammer on the anvil block 11 being transmitted to the cable sling 5 and thence by the clamp 2 to the pile. Thus the pile may be completely withdrawn and laid aside, the flexibility of the cable sling permitting this to be done before detaching the clamp.

20 In explanation of the use of this auxiliary starting device it may be said that in service, sheet piling is very often under a severe transverse strain from hydraulic pressure from the outside and that under this influence the joints between the piling become filled with sand and silt very tightly packed. 25 In addition, to this there are times when the sheet piling is used as a form and concrete is poured directly into it. In either of these cases it is very difficult to break the joints between the piling but after the pile is once 30 moved, the resistance to pulling is considerably reduced. The apparatus to which this invention appertains is particularly designed for starting the piles and breaking the joints as it has a relatively short movement and must depend on the hammer rig 35 for completion of the pulling action.

Having thus described one form of applying my invention, what I desire to claim is:—

40 1. In a pile pulling attachment a cylinder, a piston in operative relation therewith, and having relative motion thereto, means for anchoring said piston against movement, means to supply fluid under pressure to said cylinder, and an operative connection between said cylinder and a pile whereby the motion of said cylinder is transmitted through said connection to said pile.

50 2. In a pile pulling attachment, a casing, an operative connection between said casing and a pile, hydraulically operated means including a member in said casing and means for anchoring said members against movement whereby a limited pulling motion is transmitted to said pile through said connection, and additional means whereby said pulling motion is completed.

55 60 65 3. In a pile pulling attachment, a cylinder and a piston in operative relation therewith, means to hold said piston stationary relative to said cylinder, means to move said cylinder relative to said piston, and a cable sling in operative relation to said cylinder and attached to a pile, whereby the motion of said cylinder is communicated to

said pile, and means to hold an adjacent pile stationary.

4. In a pile pulling attachment, a lever arm anchored at one end, a post pivotally connected to said lever arm, means comprising a hydraulically operated piston operatively attached to said post through said lever whereby said post is forced against a pile, and means comprising a cylinder and a cable sling to transmit motion to a pile adjacent said first mentioned pile.

5. A power hammer, a cable sling around said hammer, means for attaching said sling to a pile, a supporting sling, and means for exerting an upward pull upon the hammer through the supporting sling, combined with hydraulically actuated means for forcing said hammer upwardly.

6. A power hammer, a cable sling around said hammer, means for attaching said sling to a pile, a supporting sling, and means for exerting an upward pull upon the hammer through the supporting sling, combined with hydraulically actuated means for forcing said hammer upwardly and 85 means cooperating with piles other than that to which said sling is attached, arranged to oppose the thrust of the hydraulic means.

7. In a pile pulling attachment, a cylinder, a piston, means for holding the piston against movement, a connection between the cylinder and a pile whereby motion of the cylinder is transmitted to the pile.

8. In a pile pulling attachment, a cylinder, a piston, means including a member connected to a pile and to the piston for holding the piston against movement, a connection between the cylinder and a pile adjacent the first named pile whereby motion of the cylinder is transmitted to the last named pile.

9. In a pile pulling attachment, a cylinder and a piston in operative relation therewith, means to hold said piston stationary relative to said cylinder, means to move said cylinder relative to said piston, operative connections between the cylinder and a pile, whereby the motion of said cylinder is communicated to said pile, and means to hold an adjacent pile stationary.

10. In a pile pulling attachment, a cylinder and a piston in operative relation therewith, operative connections between the cylinder and a pile, and means including a common member for holding the piston stationary and for holding the pile adjacent the first named pile stationary.

11. In a pile pulling attachment, means for lifting a pile and simultaneously exerting a downward force on the adjacent pile.

12. In a pile pulling attachment, hydraulically operable means for lifting a pile and simultaneously exerting a downward force on the adjacent pile.

13. In a pile pulling attachment, means including a cylinder and cooperating piston for lifting a pile and simultaneously exerting a downward force on the adjacent pile.
- 5 14. In a pile pulling attachment, a cylinder, a piston therein, operative connections between one of said elements and a pile to lift the pile, and operative connections between the other element and an adjacent pile to hold said pile stationary.
- 10 15. In a pile pulling attachment, a cylinder, a piston therein, operative connections between said cylinder and a pile to lift the pile and operative connections between the
- piston and an adjacent pile to hold said pile 15 stationary.
16. In a pile pulling attachment, a cylinder, a piston therein, operative connections between the cylinder, and a pile, means connected to the piston and other piles for holding the piston stationary and means connected to said last named means for holding the pile next adjacent the first named pile stationary.

In witness whereof, I hereunto set my 25
hand this 9th day of July, 1920.

MALCOLM D. RIKER.
